BLOUSE.

Specification of Letters Patent.

Patented Sept. 23, 1919.

Application filed January 4, 1919. Serial No. 269,568.

To all whom it may concern:

Be it known that we, LOUIS SCHWARTZ and HARRY ZASLAWSKY, citizens of the United States, both residing in the borough of Brooklyn, county of Kings, city and State of New York, have invented a new and useful Blouse, of which the following is a specification.

The object of the invention is to provide a blouse for school children which shall afford secure, convenient and concealed means for carrying essential articles of school equipment, such as a note-book, pencils and handkerchief, and which shall be of good appearance. The blouse has a front panel, the lower part of which is a deep and wide pocket, while the upper part has a flap continuing from the front wall of the pocket and adapted to be either fastened up or let down, in the latter condition exposing small pockets on its inner side as well as affording access to the main pocket. Other features of the invention will become apparent.

In the drawings forming a part hereof: Figure 1 is a front elevation of the blouse, with the sleeves broken away, showing the flap fastened up;

Fig. 2 is a similar view, with the upper part of the garment broken away for economy of space, showing the flap let down; and

Fig. 3 is a vertical section on the line 3—3 of Fig. 1, the thickness of the layers being exaggerated because of the necessities of illustration.

The blouse of the drawing is of the middy type, and may be made as usual with the exception of the broad front panel or section 1. The lower part of this panel, as stated, is a deep and wide pocket 2, which is permanently closed at the sides and bottom and has its entrance at the top, the pocket being particularly designed to hold a note-book 3.

The front or outer wall 4 of the pocket is extended to form a flap 5, substantially the width of the pocket, this extension of the pocket wall being free either to extend straight up over the chest as in Figs. 1 and 3, or to fold down as in Fig. 2. In the former condition it is held by a pair of buttons 6 on the upper part of the main wall 7 of the panel, which coöperates with button-holes 8 in the corners of the flap. The points at which the free side edges of the flap commence are at such height as to permit the flap to fold down over a belt 9, forming a part of the blouse without disturbing the same.

On the inner side of the flap are a number of small pockets which are exposed when the flap is folded down. Preferably these comprise a pair of narrow pencil pockets 10 and a pocket 11 between them adapted to receive a handkerchief. These pockets, it is to be noted, have their openings at the bottom and their tops permanently closed, in the buttoned-up condition of Figs. 1 and 3, that is to say the normal condition. Consequently the articles contained therein cannot fall out upon the ground when the child stoops over, and if they escape at all they will be caught in the main pocket 2. Friction and pressure tend to hold them against such displacement, and the contents of the main pocket will act as an obstruction. When the flap hangs down, on the contrary, the bottoms of the pockets 10, 11 are closed, and their tops are open. In this condition both these pockets and the main pocket are readily accessible, and when the gap is fastened up the contents of all the pockets are safeguarded. The button-holes 8 extend through and are reinforced by the pencil pockets 10.

What we claim as new is:

1. A scholar's companion blouse having a front panel, the lower part of which is a deep and wide pocket, while the upper part has a flap normally extending upward from the front wall of said pocket, of which it forms a continuation, and adapted to be let down to afford access to said pocket, and means for buttoning the flap up toward the neck of the blouse.

2. A scholar's companion blouse having a front panel, the lower part of which is a deep and wide pocket, while the upper part has a flap normally extending upward from the front wall of said pocket, of which it forms a continuation, small pockets upon the inner side of the flap, said flap being adapted to be let down to expose the small pockets and to afford access to the large pocket, and means for buttoning the flap up toward the neck of the blouse.

HARRY ZASLAWSKY.
